CLAIM

the ornamental design for a tent pole, as shown and described.

DESCRIPTION

FIG. 1 is an upper perspective view of the tent pole showing my design.

FIG. 2 is a front elevation view thereof;

FIG. 3 is a back elevation view thereof;

FIG. 4 is a top plan view thereof;

FIG. 5 is a bottom plan view thereof;

FIG. 6 is a side elevation view thereof; and,

FIG. 7 is an opposite side view thereof.

The tent pole of the present design is used on an outer periphery of a tent, supporting a frame.

The tent pole of the present design is not a center pole.
